Des. 236,974
Patented Sept. 30, 1975

236,974

MOTORCYCLE GLOVE COMPARTMENT

James F. Harris, 111 W. 32nd St. S.,
Sand Springs, Okla. 74063

Filed Apr. 26, 1974, Ser. No. 464,526

Term of patent 14 years

Int. Cl. D12—11

U.S. Cl. D12—158

FIG. 2

FIG. 1

FIG. 4

FIG. 3

FIG. 5

FIG. 1 is a front elevational view of a motorcycle glove compartment showing my new design.

FIG. 2 is a top plan view thereof.

FIG. 3 is a bottom plan view thereof.

FIG. 4 is an end elevational view thereof, it being understood that the opposite end is a mirror image of the end shown herein.

FIG. 5 is a rear elevational view thereof.

I claim:

The ornamental design for a motorcycle glove compartment, substantially as shown and described.
